PLASTIC NOZZLE OR SPOUT MOUNTING

John Henchert, River Forest, Ill., assignor to Continental Can Company, Inc., New York, N. Y., a corporation of New York

Application July 13, 1954, Serial No. 443,029

15 Claims. (Cl. 222—542)

The invention relates generally to metallic receptacles and primarily seeks to provide a novel pouring spout or nozzle mounting for such structures in which a plastic spout or nozzle is employed.

An object of the invention is to provide a mounting of the character stated which is neat in appearance and provides the desired hermetic seal.

Another object of the invention is to provide a mounting of the character stated wherein provision is made for avoiding presentation of raw metal edges interiorly of the container structure.

Another object of the invention is to provide a spout mounting of the character stated wherein the spout registering opening is turned in a manner for reinforcing the opening and imparting rigidity to the annular seat.

In its more detailed nature the invention seeks to provide a spout mounting of the character stated wherein the spout comprises a tubular externally threaded plastic body having an outwardly extending slightly downwardly dished peripheral flange, and wherein a wall of the container is equipped with an opening with which the spout opening registers and an annular seat opposed by the spout flange and defined by an upstanding wall portion formed by an annular fold in said container wall including a portion bent inwardly and downwardly over the spout flange to secure the same on the seat, there being included a sealing material on the annular seat and into which the peripheral edge portion of the spout flange is caused to securely bite by the overhanging container wall fold.

Another object of the invention is to provide a spout mounting of the character stated wherein the annular seat includes an upwardly turned edge defining the spout registering opening and which is received or embedded and shielded from view and contact in an annular clearance in the bottom face of the spout.

Another object of the invention is to provide a spout mounting of the character stated wherein the spout registering opening defining edge is turned in the form of a reinforcing hem.

A further object of the invention is to provide a spout mounting of the character stated wherein the spout registering opening defining edge is turned in the form of a downwardly and outwardly directed curl.

A still further object of the invention is to provide a spout mounting of the character stated wherein the spout includes a depending cylindrical extension snugly received in the reinforced spout registering opening.

With the above and other objects in view that will hereinafter appear, the nature of the invention will be more fully understood by following the detailed description, the appended claims and the several views illustrated in the accompanying drawings.

In the drawings:

Figure 1 is a fragmentary vertical cross sectional view illustrating one form of spout mounting, parts being broken away and in section.

Figure 2 is an enlarged fragmentary sectional view illustrating the mounting of Figure 1.

Figure 3 is a view similar to Figure 2 illustrating a modified form of mounting wherein the spout registering open-

2

ing is reinforced by an outwardly or upwardly turned hem.

Figure 4 is a view similar to Figure 2 illustrating another modified form of mounting wherein the spout registering opening is reinforced by an inwardly or downwardly turned hem, the spout also including a cylindrical extension snugly fitting within the opening.

Figure 5 is a view similar to Figure 4 illustrating still another modified form of mounting wherein the spout registering opening is reinforced by a downwardly and outwardly directed curl.

In the form of the invention shown in Figures 1 and 2 the novel spout mounting is illustrated as incorporated in a container top or breast 5 which is secured by a conventional double seam 6 to a container body 7. The spout or nozzle generally designated 8 is in the form of a tubular body 9 which is externally threaded at 10 and preferably formed of polyethylene, a resilient deformable plastic, although it is to be understood that the same may be formed of other plastics, including those which harden upon curing. The tubular body 9 includes an outwardly projecting flange 11 at its lower end extremity, and this flange is slightly dished downwardly to provide a peripheral dip at 12. The breast or top 5 has an annular horizontal seat 13 within the center of which a spout registering opening 14 is provided. In this instance the opening is defined and reinforced by an upturned edge 15. It will be apparent by reference to Figure 2 that the reinforcing edge is turned upwardly at an angle of 90°. The seat 13 is defined outwardly by an upstanding wall in the form of an annular fold 16 including a portion 17 bent inwardly and downwardly over the spout flange 11. A sealing compound 18 is provided on the seat beneath the flange 11, and the overbending of the fold at 17 serves to cause the flange dip 12 to firmly bite into the sealing compound and form a very efficient seal in the manner clearly illustrated in Figure 2. The upturned reinforcing edge 15, either through force of mounting, as when a deformable plastic such as polyethylene is employed, or by provision of a preformed groove if a hard plastic nozzle or spout is employed, bites into the nozzle at 19 and is shielded from view and contact in the manner clearly illustrated in Figures 1 and 2. In this manner presentation of raw metal edges internally of the container is avoided.

In Figure 3 a slightly modified form of mounting is illustrated. This mounting is the same as the previously described mounting except for the fact that there is no embedding of the spout registering opening reinforcing edge into the base of the spout or nozzle. In this modified mounting the reinforcing of the opening defining edge is by an outwardly or upwardly directed hem 20.

In Figure 4 of the drawing another slight modification of the mounting is illustrated wherein the reinforcing of the spout registering opening defining edge is by a downwardly or inwardly directed hem 21, and in this mounting the spout or nozzle also is shown as including a cylindrical extension 22 which depends from the spout through the top or breast opening and snugly fits within the hem 21.

Another slightly modified mounting is illustrated in Figure 5. In this form of the invention the reinforcement of the nozzle or spout registering opening is by way of forming a downwardly and outwardly directed curl 23 in the opening defining edge. The spout or nozzle may also be provided with a cylindrical extension 24 depending within and snugly fitting the curl in the manner illustrated.

It is to be understood that in each of the previously described mountings the nozzle or spout is pressed against the sealing compound covered receiving seat while the seat defining fold 16 is in upstanding condition. After

this preliminary application the fold is bent over at 17 as previously described to secure the spout in place and firmly press the peripheral flange dip into the underlying sealing compound. This attachment serves to firmly press the angle turned edge 15 into the deformable base of the spout if polyethylene or a comparably soft plastic is employed, or it will serve to hold said edge in the preformed groove provided in the base of a spout formed of a hard plastic.

Example mountings illustrating the invention have been disclosed herein but it is to be understood that variations in the structure and arrangement of the parts may be provided without departing from the spirit and scope of the invention as defined in the appended claims.

I claim:

1. In a container structure, a plastic nozzle comprising a tubular body including a base portion having a flange projecting radially outwardly with respect to the axis of the nozzle, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, the seat edge portion defining said opening being turned to provide a reinforced edge imparting rigidity to the seat.

2. In a container structure, a plastic nozzle comprising a tubular body including a base portion having a flange projecting radially outwardly with respect to the axis of the nozzle and which is slightly dished to provide a peripheral dip, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, there being included a sealing compound on the seat and in which the peripheral dip of the nozzle flange is caused to securely bite by the overhanging annular wall fold.

3. In a container structure, a plastic nozzle comprising a tubular body including a base portion having a flange projecting radially outwardly with respect to the axis of the nozzle, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, the seat edge portion defining said opening being turned upwardly in the form of a hem to avoid presentation of a raw metal edge inwardly of the container and to provide a reinforced edge imparting rigidity to the seat.

4. In a container structure, a plastic nozzle comprising a tubular body including a base portion having a flange projecting radially outwardly with respect to the axis of the nozzle, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, the seat edge portion defining said opening being turned in the form of a hem to provide a reinforced edge imparting rigidity

to the seat, and the nozzle including a cylindrical extension at its base portion snugly received in the reinforced seat opening.

5. In a container structure, a plastic nozzle comprising a tubular body including a base portion having a flange projecting radially outwardly with respect to the axis of the nozzle, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, the seat edge portion defining said opening being turned in the form of a downwardly and outwardly directed curl to provide a reinforced edge imparting rigidity to the seat.

6. In a container structure, a plastic nozzle comprising a tubular body including a base portion having a flange projecting radially outwardly with respect to the axis of the nozzle, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, the seat edge portion defining said opening being turned in the form of a downwardly and outwardly directed curl to provide a reinforced edge imparting rigidity to the seat, and the nozzle including a cylindrical extension at its base portion snugly received in the reinforced seat opening.

7. In a container structure, a plastic nozzle comprising a tubular body including a base portion having a flange projecting radially outwardly with respect to the axis of the nozzle, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, the nozzle being formed of a deformable plastic, and the seat edge portion defining said opening being turned upwardly at an angle of approximately 90° and held embedded in the base portion of the nozzle and thereby shielded from view and contact.

8. In a container structure, a plastic nozzle comprising a tubular body including a base portion having a flange projecting radially outwardly with respect to the axis of the nozzle, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, the seat edge portion defining said opening being turned upwardly at an angle of approximately 90° and shielded from view and contact in a preformed annular groove in the nozzle base portion.

9. In a container structure, a plastic nozzle comprising a tubular body including a base portion having a flange projecting radially outwardly with respect to the axis of the nozzle and which is slightly dished to provide a peripheral dip, and a mounting wall having an annular seat generally flat and in a plane traversing the axis of the nozzle and on which to receive the nozzle base portion and its

flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, there being included a sealing compound on the seat and in which the peripheral dip of the nozzle flange is caused to securely bite by the overhanging annular wall fold, the seat edge portion defining said opening being turned to provide a reinforced edge imparting rigidity to the seat.

10. In a container structure, a plastic nozzle comprising a tubular body including a base portion having a flange projecting radially outwardly with respect to the axis of the nozzle and which is slightly dished to provide a peripheral dip, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, there being included a sealing compound on the seat and in which the peripheral dip of the nozzle flange is caused to securely bite by the overhanging annular wall fold, the nozzle being formed of a deformable plastic, and the seat edge portion defining said opening being turned upwardly at an angle of approximately 90° and held embedded in the base portion of the nozzle and thereby shielded from view and contact.

11. In a container structure, a plastic nozzle comprising a tubular body including a base portion having a flange projecting radially outwardly with respect to the axis of the nozzle and which is slightly dished to provide a peripheral dip, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, there being included a sealing compound on the seat and in which the peripheral dip of the nozzle flange is caused to securely bite by the overhanging annular wall fold, the seat edge portion defining said opening being turned upwardly at an angle of approximately 90° and shielded from view and contact in an annular groove formed in the nozzle base portion.

12. In a container structure, a plastic nozzle comprising a tubular body including a base portion having a flange projecting radially outwardly with respect to the axis of the nozzle and which is slightly dished to provide a peripheral dip, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, there being included a sealing compound on the seat and in which the peripheral dip of the nozzle flange is caused to securely bite by the overhanging annular wall fold, the seat edge portion defining said opening being turned in the form of a hem to provide a reinforced edge imparting rigidity to the seat, and the nozzle including a cylindrical extension at its base portion snugly received in the reinforced seat opening.

13. In a container structure, a plastic nozzle comprising a tubular body including a base portion having a

flange projecting radially outwardly with respect to the axis of the nozzle and which is slightly dished to provide a peripheral dip, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, there being included a sealing compound on the seat and in which the peripheral dip of the nozzle flange is caused to securely bite by the overhanging annular wall fold, the seat edge portion defining said opening being turned upwardly in the form of a hem to avoid presentation of a raw metal edge inwardly of the container and to provide a reinforced edge imparting rigidity to the seat.

14. In a container structure, a plastic nozzle comprising a tubular body including a base portion having a flange projecting radially outwardly with respect to the axis of the nozzle and which is slightly dished to provide a peripheral dip, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, there being included a sealing compound on the seat and in which the peripheral dip of the nozzle flange is caused to securely bite by the overhanging annular wall fold, the seat edge portion defining said opening being turned in the form of a downwardly and outwardly directed curl to provide a reinforced edge imparting rigidity to the seat, and the nozzle including a cylindrical extension at its base portion snugly received in the reinforced seat opening.

15. In a container structure, a plastic nozzle comprising a tubular body including a base portion having a flange projecting radially outwardly with respect to the axis of the nozzle and which is slightly dished to provide a peripheral dip, and a mounting wall having an annular seat generally flat and in a plane traversing the axis of the nozzle and on which to receive the nozzle base portion and its flange, said seat being defined inwardly by an opening registering with the opening through the tubular nozzle and outwardly by an upstanding wall portion formed by an annular fold in said mounting wall, said fold including a portion bent inwardly and downwardly over the flange to secure the same on the seat, there being included a sealing compound on the seat and in which the peripheral dip of the nozzle flange is caused to securely bite by the overhanging annular wall fold, the seat edge portion defining said opening being turned to provide a reinforced edge imparting rigidity to the seat, and the nozzle including a cylindrical extension at its base portion snugly received in the reinforced seat opening.
